Primary Examiner—Doris V. Coles*Attorney, Agent, or Firm*—David L. Baker; Rhodes & Ascolillo[57] **CLAIM**

The ornamental design for a combination land and water rotating decoy mount, as shown and described.

DESCRIPTION

FIG. 1 is a perspective view of a combination land and water rotating decoy mount showing our new design therefor. The broken line drawing representing a decoy in place is for purposes of illustration only and forms no part of our design.

FIG. 2 is a front elevational view;

FIG. 3 is a rear elevational view;

FIG. 4 is a right side elevational view;

FIG. 5 is a bottom plan view; and,

FIG. 6 is a top plan view.
